(57) **CLAIM**

The ornamental design for a packaging bag containing individually wrapped contents, as shown and described.

DESCRIPTION

The patent or application file contains at least one drawing executed in color. Copies of this patent or patent application publication with color drawing(s) will be provided by the Office upon request and payment of the necessary fee.

1. Packaging bag containing individually wrapped contents

1.1 : Front Perspective View

1.2 : Back Perspective View

1.3 : Front

1.4 : Back

1.5 : Top

1.6 : Bottom

1.7 : Right Side View

1.8 : Left Side View

The “Elis” logo including three Japanese letters beneath forming part of the claimed design is a registered trademark of Daio Paper Corporation. The long-long dash broken lines shown in reproductions 1.1 and 1.5 represent perforations and do form part of the claimed design; the short-short dash

(Continued)

broken lines shown in the reproductions depict environmental structure only and form no part of the claimed design.
